CLAIM

The ornamental design for the candle warming tower, as shown and described.

DESCRIPTION

FIG. 1 is an elevated, perspective view of a candle warming tower in accordance with an embodiment of my invention;

FIG. 2 is a side view of the embodiment of FIG. 1;

FIG. 3 is a side view opposite that of FIG. 2;

FIG. 4 is another side view of the embodiment of FIG. 1;

FIG. 5 is a side view opposite that of FIG. 4;

FIG. 6 is a top view of the embodiment of FIG. 1; and,

FIG. 7 is a bottom view of the embodiment of FIG. 1.
